TOY BALL

Virginia D. Da Costa, Providence, R. I., assignor
to Da Costa Toy Company, a corporation of
Rhode Island

Application December 15, 1936, Serial No. 115,977

3 Claims. (Cl. 46—91)

My invention relates to transparent, hollow toys partly filled with liquid, and aims to improve the appearance of such articles.

One object of the invention is to provide means in articles of the character mentioned which will impart a vari-colored effect thereto.

Another object of my invention is to provide means in such articles for giving a kaleidoscopic effect when the toy is rolled.

10 With these and other objects in view, the invention consists of certain novel features of construction, as will be more fully described, and particularly pointed out in the appended claims.

In the accompanying drawings:

15 Fig. 1 is a perspective view of a one face toy embodying my invention;

Fig. 2 is a central vertical section through the article illustrated in Figure 1;

20 Fig. 3 is a perspective view of another form of my invention;

Fig. 4 is a central vertical section through the article illustrated in Figure 3;

25 Fig. 5 is a perspective view of the movable members within the ball.

25 The present invention is an improvement on a known form of toy which comprises a hollow, transparent body partly filled with liquid and containing a float. Ordinarily, the body is made from transparent celluloid in two parts and the

30 parts hermetically sealed together while the liquid employed is commonly water. The float employed is colored in a bright attractive manner to catch the eye of observers. For manufacturing reasons, the external bodies of such articles have commonly been made spherical, but this is optional. I

35 have found that the attention of persons in the neighborhood of such toys or articles can be more surely attracted thereto and held thereby for a longer period if the toys are given a vari-colored

40 effect and especially if a kaleidoscope effect can also be produced when the toy is rolled; and the following is a more detailed description of two present embodiments of this invention, illustrating the preferred means by which these advan-

45 tageous results may be accomplished.

With reference to Figures 1 and 2 of the drawings, 10 designates a hollow body or shell of transparent material, shown as having a spherical or globular form, although the form of the body 10 is

50 not essential. The body 10 is shown as formed of two parts and is made of transparent celluloid, or other light strong transparent material, and contains a body of a liquid whose surface is indicated at 12. Water is a satisfactory liquid to

55 use in the body 10. Ordinarily, the body 10 con-

tains a float 14, shown in the form of a fish in Figure 1. In accordance with my invention, I provide in the body 10 a plurality of different colored solid objects or bodies 16, 16 heavier than the water or other liquid in the toy and individually small compared to body 10. Preferably, there are a considerable number of such objects 16, say 20 or more. The objects 16 have various colors as indicated by the different shadings applied thereto in Figure 2, and may consist of pieces of colored agate, quartz or like colored stone, or pieces of mother-of-pearl or iridescent shell, especially if stained or dyed different colors. Some or all of objects 16 may be individually variegated as to color. Such objects should be inert to the water 15 or other liquid in the toy so that it will not dissolve them or attack them to muddy the liquid or change the colors of the objects.

The objects 16 naturally collect in the bottom of the toy and, when the toy is viewed at a certain angle, objects 16 can be seen simultaneously two ways, one in magnified form through the lower wall of the body 10, and the other in actual size through the upper portion of the wall of body 10 and through the surface of the liquid. 20 Such effect is illustrated in Figure 1 where the objects 16 are shown in two positions, the lower image enlarged or magnified and the upper one relatively smaller. The way in which such an effect is produced is illustrated somewhat diagrammatically in Figure 2 by lines 18, 18' and 20, 20' representing two light rays, both leaving the objects 16 in the bottom of the body 10 and converging at the point 22 which is assumed to be the eye of the observer. In addition to such double images shown in full lines in Figure 1, a 25 number of shadowy or partial images of the objects 16 may often be obtained under different lighting conditions as indicated by reference characters 16 on Figure 1 enclosed in dotted circles and having dotted lead lines.

More especially, the colors from objects 16 are reflected in the liquid 12 and from its surface and the surface of body 10 in various ways in producing indefinite images or colored shadows in 45 the liquid and thereby greatly enhancing the appearance of the toy. For example, when the article is viewed from above and especially in a strong light, a colored ring, which may be of one or more colors appears around the edge of the 50 liquid surface. It is thought that the fillet 24 at the edge of the meniscus plays a part in producing or magnifying this effect.

Further examples of the ways in which the objects 16 may produce different colored effects 55

in the liquid 12 are indicated by two different sets of broken lines in Figure 2. One set of lines is indicated by reference characters 28, 28 and 28', 28', and the other set of lines is indicated by reference numerals 28, 28 and 28', 28'. The lines 28 represents rays of light leaving the objects 16 and passing through the surface of the liquid so as to strike the inner face of the ball 10 at points 27, 27. Some of rays 28 are reflected as indicated by reference characters 28' and thereupon pass back through the surface of the liquid 12 and strike the wall of the ball 10 at points 27', 27', beneath the surface of the liquid. The colors of the objects 16 therefore will appear to the observer who is looking at either of the points 27 or 27'. In a similar way, the rays 28 leaving the objects 16 and passing through the surface of the liquid 12 strike the inner face of the ball 10 at points 29, 29 and are then partly reflected so as to pass again through the surface 12 and strike the inner face of the body 10 at points 29', 29', the portion of the rays 28 being reflected at points 29 being indicated by the lines having reference characters 28' applied thereto. Colors therefore appear to persons looking at points 29 and 29'. However, I do not limit myself to any particular optical theory as to how the colors or other pleasing effects of my invention are produced.

In general, the description of Figures 1 and 2 given above applies also to the embodiment of my invention illustrated in Figures 3 and 4. The portions of the description of Figures 1 and 2 and the reference characters used therein which apply equally to Figures 3 and 4 will not be repeated. The toy of Figures 3 and 4, however, differs from that of Figures 1 and 2 in that, instead of employing different colored objects such as 16 of Figures 1 and 2 having somewhat irregular forms, the toy of Figures 3 and 4 has inside it a plurality of different colored flat objects 16', the differences in color indicated by shading, those illustrated being disks cut from different colored sheets of celluloid. The optical effects produced by objects 16' are substantially the same as those above described with respect to objects 16, the disks 16' being heavier than the water, or other liquid employed, mostly gather in a mass as shown at the bottom of the toy when it is stationary. Due to their small size and flat form, however, objects 16' tend to adhere to the inner surface of the body 10 and some of them are carried around by it when the toy is rolled so as to increase the kaleidoscopic effect. The adhesion between the disks and the body, however, is quite slight and the disks can be washed loose from the portion of body 10 above the liquid level when so desired by merely shaking it.

While I have illustrated floats in both Figures 1 and 3, I do not limit myself to the use of such a feature.

The foregoing description is directed solely towards the construction illustrated, but I desire it to be understood that I reserve the privilege of

resorting to all the mechanical changes to which the device is susceptible, the invention being defined and limited only by the terms of the appended claims.

I claim:

1. A toy comprising a hollow transparent globular shell having an outer convexly curved surface, said shell being partly filled with a liquid to provide an upper refracting surface of a substantial extent, and a plurality of differently colored objects loosely positioned within said shell comprising a material heavier than the liquid and insoluble and inert with respect thereto, said objects being movable to different positions along the inner curved surface of the shell upon a rolling movement of the toy, said inner shell surface being of such a character that there is reflected to the eye of an observer angularly glancing at the ball a double image of the objects therein, one of said images being seen in magnified form through the lower wall of the shell, while the other image can be seen in actual size through the wall of the upper portion of the shell and being reflected through the surface of the liquid therein, said images being reflected upwardly as converging light rays passing through said liquid to the eye of the observer.

2. A toy comprising a hollow transparent globular shell having an outer convexly curved surface, said shell being partly filled with a liquid to provide an upper refracting surface, and a plurality of differently colored objects loosely positioned within said shell comprising a material heavier than the liquid and insoluble and inert with respect thereto, said objects being movable to different positions along the inner curved surface of the shell upon a rolling movement of the toy, said inner shell surface being of such a character that there is reflected to the eye of an observer angularly glancing at the ball a double image of the objects therein, one of said images being seen in magnified form through the lower wall of the shell, while the other image can be seen in actual size through the wall of the upper portion of the shell and being reflected through the surface of the liquid therein, said images being reflected upwardly as converging light rays passing through said liquid to the eye of the observer, said objects comprising flat disks capable of adhering to the inner surface of the shell.

3. A toy comprising a hollow transparent globular shell of celluloid composition having an outer convexly curved surface, said shell being partly filled with a liquid to leave a free space above the same, and a plurality of differently colored flat disks loosely positioned within said shell comprising a material heavier than the liquid and insoluble and inert with respect thereto, said disks adhering to the wall of the free space upon slow movement of the toy by reason of the adhesion of the liquid to the shell and to the disks.

VIRGINIA D. DA COSTA.
